UNITED STATES PATENT OFFICE.

ALEXANDRE M. GREAN, OF NEW YORK, N. Y.

SHOULDER-FORM.

No. 810,332.

Specification of Letters Patent.

Patented Jan. 16, 1906.

Application filed June 2, 1905. Serial No. 263,469.

To all whom it may concern:

Be it known that I, ALEXANDRE M. GREAN, a citizen of the United States, residing in the borough of Manhattan, city, county, and State of New York, have invented a new and useful Improvement in Shoulder-Forms, adapted to be used in garments for either the male or female sex; and I do declare the following to be a clear and exact description of the nature thereof, so that those skilled in the art to which my invention applies may make use and fully understand the same, reference being had to the accompanying drawings, which are part of this specification, and are fully described, and defined specifically in the claims.

This invention relates to wearing-apparel, and pertains especially to shoulder-forms.

The object of the invention is to provide a shoulder-form of such novel and peculiar shape and construction as to fit the shoulder of a person and follow the lines at the top, back, and front of the shoulder more perfectly than is possible with the ordinary shoulder-forms.

25 A further object of the invention is to provide a shoulder-form one part of which is adapted to follow the lines of the shoulder of a person closely and the other part of which is arranged to remedy defects in the shoulder 30 and to hold the shoulder of a garment in shapely position.

With these and various other objects, advantages, and improved results in view the invention consists of a shoulder-form having 35 sides which curve inwardly, a top shaped into a compound curve, and a deeply-arched portion tapering into a shallow-arched end, with points at the intersection of the said portion and the sides—that is, the form is shaped or 40 molded so that the concavity diminishes in depth from the outer to the inner end of the form.

In the accompanying drawings, forming 45 part of this application, Figure 1 is a perspective view. Fig. 2 is an inverted plan view. Fig. 3 is a central longitudinal section partly broken away. Fig. 4 is a cross-section on the line $x-x$, Fig. 2. Fig. 5 is a cross-section on the line $y-y$, Fig. 2. Fig. 6 is a cross-section 50 on the line $z-z$, Fig. 2.

The same numeral-references denote the

same parts throughout the several views of the drawings.

The article is molded or shaped out of any suitable material, such as felt or tailors' canvas, to form an outer portion or end 1, deeply arched or circular-shaped in cross-section. The sides 2 curve inwardly, and at the intersection of the sides and the end 1 is formed points 3, adapted to fit the front and back of a person's shoulder. The sides 2 taper from their curvature and terminate in an inner shallow arched or concaved end 4. The ends 1 and 4 will be hereinafter designated as "shoulder" and "neck" ends, respectively. 65 The top of the form has a compound curve, so as to present a convexed concaved surface lengthwise from one of said ends to the other and with the said arches diminishes in depth from the shoulder end to the neck end, leaving the latter nearly flat. The edges 5 have their deepest curve opposite the deepest part of the compound curve, and from said part said edges are straight to the neck end. This end may be cut off to shorten the form as desired. A series of pads 6 are attached under the shoulder end. Said pads overlap each other, and all of them have their outer edge flush with the edge of the shoulder end. The form is provided with a series of apertures 7 80 to lessen the weight of the form and for ventilation.

It will be seen that the form converges in curves from the large or shoulder end to the small or neck end and that the number of 85 pads may be increased or diminished, according to the desired elevation of a garment-shoulder without detaching the form or changing the shape thereof.

It will be understood that the flexibility of 90 the form will permit its being shaped as desired after it has been placed in position.

Having thus described my invention, what I claim as new, and desire to secure by Letters Patent, is—

1. As a new article of manufacture, a shoulder-form for garments comprising a fabric sheet having a shoulder end curved lengthwise and crosswise, and a flattened neck end, the contour of the form being in compound 100 curves.

2. As a new article of manufacture, a shoul-

der-form for garments comprising a fabric sheet having a flattened neck end, a padded shoulder end curved lengthwise and crosswise and elevated above the neck end, and a series of apertures from the neck end to the pads, the whole contour of the form being in compound curves, substantially as shown and described.

In testimony whereof I have hereunto signed my name to the foregoing specification in the presence of two subscribing witnesses.

ALEXANDRE M. GREAN.
